UNITED STATES PATENT OFFICE.

NATHANIEL B. STONE, OF OUTLOOK, WASHINGTON.

COMBINED TABLE AND COUCH.

No. 893,031.

Specification of Letters Patent.

Patented July 14, 1908.

Application filed January 12, 1905. Serial No. 240,746.

To all whom it may concern:

Be it known that I, NATHANIEL B. STONE, a citizen of the United States, residing at Outlook, in the county of Yakima and State of Washington, have invented a new and useful Combined Table and Couch, of which the following is a specification.

The present invention relates particularly to improvements in articles of furniture of that type which may be employed either as operating tables or couches, though undoubtedly useful for other purposes of an analogous nature.

One of the objects is to provide, in connection with a top member and a base member, means of a novel and comparatively simple nature, whereby the top member may be easily and yet positively elevated and lowered in a direct path and, when in its elevated position, may be rigidly and efficiently supported.

A further object is to provide means which will permit the free movement of the article of furniture when in the form of a couch or sofa, and which will constitute an immovable support when said article is converted into an operating table.

There are two embodiments of the invention illustrated in the accompanying drawings, and described in the following specification.

In the drawings: Figure 1 is a perspective view of the preferred form of structure, showing the same as a table. Fig. 2 is a perspective view when the article of furniture is converted into a couch or sofa. Fig. 3 is a top plan view of the structure with the upholstered top or seat removed. Fig. 4 is a longitudinal sectional view through the structure when arranged as a table. Fig. 5 is a similar view when arranged as a couch. Fig. 6 is a cross sectional view taken on the line 6—6 of Fig. 4. Fig. 7 is a detail sectional view on an enlarged scale taken on the line 7—7 of Fig. 5. Fig. 8 is a detail sectional view through the actuating crank. Fig. 9 is a top plan view of a slightly modified form of structure, the top or seat being removed. Fig. 10 is a longitudinal sectional view therethrough.

Similar reference numerals designate corresponding parts in all the figures of the drawings.

Referring first to the embodiment illustrated in Figs. 1—8, inclusive, a base member and a top member are employed, respec-

tively designated as a whole by the reference numerals 11 and 12. The base member 11 consists, preferably, of a metallic frame, comprising longitudinal side bars 13, joined by spider bracing 14 and transverse brace rods 15, said side bars 13 carrying at their ends, legs or feet 16. These legs, as shown in Fig. 5, are rigidly attached to the side bars 13 by means of depending terminal portions 17, secured to the inner sides thereof and are provided with inwardly extending end portions 16^a. The top member 12 preferably consists of a frame comprising side and end rails 18, constituting, in effect, a boxing the cover of which is formed by an upholstered cushion top or seat 19, detachably fitted within said rails.

The top member is adapted to be elevated above and lowered upon the base member, and for this purpose the following mechanism is preferably provided. Standards are employed at the different corners of the structure, each standard comprising a lower section 20, and an upper section 21, the sections being hinged together, as shown at 22. The lower section is pivoted at its lower end to the inner side and contiguous to the lower end of one of the legs or feet 16, the pivot, shown at 23, preferably passing through the downturned brace terminal 17 of the side bar 13. The lower sections 20 at each end of the structure are preferably connected by tie rods 24 and said sections swing to upright position against the inwardly extending portion 16^a of the legs, said portions thereby constituting abutments. The upper sections 21 are considerably shorter than the lower sections and constitute, in effect, arms rigidly secured to shafts 25, journaled in the ends of the top member 12 and transversely thereof. It will therefore be clear that, when the shafts 25 are rotated in one direction, the sections of the standards will be brought into alignment and the top member elevated, as shown in Fig. 1, and, on the other hand, when said shafts are revolved in an opposite direction, the sections will fold together and because of the shorter sections or arms 21, when so folded, said sections will assume an upright relation, as clearly illustrated in Fig. 5. In this latter position the top member is seated upon the base member and a couch or sofa is formed, as shown in Fig. 2. When elevated, the structure is converted into a table, as illustrated in Fig. 1.

For the purpose of revolving the shafts

and thereby swinging the sections of the standards to elevate or lower the top member, the following mechanism is preferably employed. The shafts 25 are provided with 5 pulleys or wheels 26, rigidly secured thereto, and connecting these pulleys are crossed cables 27, separate from each other, one cable wrapping upon one of the pulleys and unwinding from the other, and said cables passing around opposite sides of the same pulley, which is, in effect, a double pulley, as illustrated in Fig. 3. It will thus be clear that, by means of these connections, the shafts must, of necessity, revolve together and in 10 opposite directions, and, in order to prevent lost motion, the cables are provided with turn buckles 28, whereby the proper tautness may at all times be maintained. One of the shafts, furthermore, is provided with a gear wheel 29, and meshing therewith is a 15 pinion 30, carried by a stub shaft 31, that projects through one of the side rails 18 of the top member and has feathered thereon an actuating crank 32, said crank being slidable upon said shaft. The free end of the 20 actuating crank is provided with a handle 33, slidable transversely of said crank for the purpose hereinafter set forth.

From the above it will be seen that, when 25 the handle crank is revolved, the shafts will be rotated, and thus the sections of the standards swung to effect the raising and lowering of the top member, the actuating means being all carried by the top member. For 30 the purpose of securing the vertical movement only of the top member and preventing the swaying of said top member longitudinally during its raising and lowering movement, compensating braces are employed, 35 comprising yokes 34, the terminals of which are pivoted upon the cross braces 15 of the base member, these yokes having connected to their intermediate portions links 35, which links are, in turn, journaled on crank pins 40 36, carried by the pulleys 26, said pulleys therefore constituting crank elements. The 45 connections between the links 35 and yokes 34 are adjustable, as shown at 37, in order that proper tension may be placed 50 upon the braces. Assuming the parts in the position shown in Fig. 4, it will be seen that 55 crossed braces are thus provided between the base and top members which rigidly hold the same, and, as the shafts rotate during the lowering of the table, the crank pins 36 will be turned, so that the proper strain will at all 60 times be maintained upon these braces, and the top member will thus be held against swaying and can have only a vertical or up-right path of movement.

It will be clear to those skilled in the art 65 that an easily movable couch or sofa is advantageous, but that an operating table must have a firm immovable foundation. Therefore, one of the important features of

the invention relates to means for effecting these changes when the article of furniture is converted into either. In the present embodiment upright plungers 38 are employed, which are slidable in the feet or legs 16 of the 70 base member. The lower ends of these plungers carry rollers or casters 39, adapted to be seated in recesses 40 in the lower ends of said feet or legs so that the latter may rest firmly upon the floor. When in such relation, the 75 upper ends of the plungers 38 project above the base member and are adapted to be borne against by blocks 41, carried by the side rails 18 of the top member. Now it will be apparent that, when the top member is elevated 80 from the base member and the article of furniture is converted into a table, the plungers 38 will slide freely through the feet or legs 16, the casters will seat themselves in the recesses 40, and consequently, said feet or legs 85 will rest firmly upon the floor or surface supporting the device. When, however, the top member is lowered, it will rest upon said plungers, and the doubling of the standards will draw the base member upwardly, so that 90 the casters will rest upon the floor and the sofa can be readily moved.

Under ordinary conditions the structure will, of course, be in the form of a sofa, and, as shown in Fig. 2, the crank arm 32 is 95 moved inwardly and the handle 33 is moved in a similar direction, an opening being provided in the adjacent side rail to receive said handle. This is the only element of the mechanism that is exposed, and it will be 100 apparent that the same may be placed toward the wall so that it will not be seen. When it is desired to employ the structure as an operating table, the patient is placed upon the sofa, and the crank and handle 105 drawn outwardly and revolved. The result is that the sections of the standards are swung into alignment, and consequently the top member is elevated. The parts are so arranged that the crank will assume a position which will permit the handle 33 being passed behind the adjacent standard, as 110 illustrated in Fig. 1, and thus the mechanism is positively locked against movement. The employment of short arms or sections on the 115 shafts is important, as a more direct bearing is secured between the connections at the ends of the standards, a greater power is obtained, and, as the shorter sections revolve through nearly a half circle, a comparatively 120 great elevation of the top member can be secured with comparatively short standards and great power.

A slightly different embodiment of the invention is illustrated in Figs. 9 and 10. In 125 view of the fact that the base and top members, together with the standards, shafts and braces are exactly the same as those already described, the same reference numerals have been employed in connection therewith, as 130

it is thought to be unnecessary to practically duplicate the description already given. The difference resides in the means for actuating and effecting the simultaneous movement of the shafts 25. In this instance, the compensating brace links 35 are connected to crank elements 42, in the form of wheels rigidly attached to the shafts 25. These wheels are in the nature of worm gears, being provided with worm teeth 43. An actuating shaft 44 extends longitudinally through the top member and is provided with opposite worms 45, respectively intermeshing with the wheels 42. One end of the shaft 44 projects through the adjacent end rail of the top member and has a crank arm 46, provided with a handle 47. It will be seen that, when this crank arm is rotated in one direction or the other, the wheels 42 will be turned in opposite directions, thereby effecting the same raising or lowering movement of the top member as has been already described.

From the foregoing it is thought that the construction, operation, and many advantages of the herein described invention will be apparent to those skilled in the art, without further description.

Having thus described my invention what I claim as new and desire to secure by Letters Patent, is:

1. In a convertible couch and table structure, the combination with a base member, of a top member movably associated therewith, a standard comprising hingedly connected sections pivoted respectively to the members and movable to substantially alined upright positions to elevate the top member, a stop portion carried by one member and abutted against by one side of the standard when the sections are alined, and means for swinging the sections into and out of alinement.

2. In a convertible couch and table structure, the combination with a base member having legs provided with inwardly extending stops or abutment portions, of a top member movably associated with the base member, standards connecting the base and top member and comprising hingedly connected sections, the lower of said sections being pivoted at their lower ends to the inner sides of the legs and swinging against the inwardly extending abutment portions thereof, the upper sections being pivoted to the top member, and means carried by and movable upon the top member for swinging the sections.

3. In an article of the class described, the combination with base and top members, of means connecting the members for raising and lowering the top member, said means including rotatable shafts journaled on one member, and standards consisting of hingedly connected sections connected to the

shafts and to the other member, a crank element carried by one of the shafts, and a brace link connected to said other member and to the crank element.

4. In an article of the class described, the combination with base and top members, of means connecting the members for raising and lowering the top member, said means including rotatable shafts journaled on one member, one of said shafts having a crank element, a yoke having its ends connected to the opposite side portions of the other member, and a link connecting said yoke and the crank element.

5. In an article of the class described, the combination with a base member, of a top member, a shaft journaled on one of the members, spaced standards comprising hingedly connected sections, each of said standards having one of its sections hinged to the shaft, and the other hinged to the other member, a crank element mounted on the shaft and swinging the standards, and a brace pivoted to the crank element and to said other member.

6. In an article of the class described, the combination with base and top members, of means for elevating and lowering the latter, said means including swinging connections between the members, separate shafts mounted on one of the members for swinging said connections, separate crossed connections between the shafts for effecting their simultaneous movements, and means for operating the shafts.

7. In an article of the class described, the combination with base and top members, of means for elevating and lowering the latter, said means including swinging connections between the members, separate shafts mounted on one of the members and attached to said connections for swinging the same, separate crossed connections between the shafts for effecting their simultaneous movements, and actuating means connected to one of the shafts.

8. In an article of the class described, the combination with base and top members, of means for elevating and lowering the latter, said means including swinging connections between the members, separate shafts mounted on one of the members for swinging said connections, crossed cables connecting the shafts and extending around opposite sides thereof, for simultaneously rotating them in opposite directions, and actuating means separate from the cables and connected to one of the shafts.

9. In an article of the class described, the combination with base and top members, of means for elevating and lowering the latter, said means including shafts journaled on one of the members, oppositely swinging connections between the shafts and the other mem-

- ber, pulleys carried by the shafts, crossed cables connecting the pulleys, and an actuating device geared to one of the shafts.
10. In an article of the class described, the combination with base and top members, of means for elevating and lowering the latter, said means including spaced shafts journaled on the top member, oppositely swinging jointed sections connected to the shafts and 10 to the base member, pulleys secured to the shafts, crossed cables connecting the pulleys, a gear wheel secured to one of the shafts, and an actuating crank having a gear connection with said gear wheel.
15. 11. In an article of the class described, the combination with base and top members, of means connecting the members for raising and lowering the top member, crossed braces connected to one member, and connections 20 between the raising and lowering means and the braces for maintaining the latter taut when the top member is in different positions.
12. In an article of the class described, the combination with base and top members, of means connecting the members for raising and lowering the top member, said means including actuating mechanism located at the 25 ends of one member, crossed braces connected to the ends of the other member, and connections between the actuating mechanism and the braces for maintaining the latter taut when the top member is in different positions.
30. 13. In an article of the class described, the combination with base and top members, of means connecting the members for raising and lowering the top member, said means including rotatable actuating devices located 35 at the ends of one member, and braces, each connected at one end to one end portion of the other member and having a crank connection with the actuating device located at the opposite end of the first mentioned member.
40. 14. In an article of the class described, the combination with base and top members, of means connecting the members for raising and lowering the top member, said means including rotatable shafts journaled on one 45 member and having crank elements, and brace links connected to the other member and to the crank elements.
50. 15. In an article of the class described, the combination with base and top members, of means connecting the members for raising and lowering the top member, said means including rotatable shafts journaled on one member and having crank elements, yokes 55 having their ends connected to the opposite side portions of the other member contiguous to its ends, and links secured to said yokes and to the crank elements.
60. 16. In an article of the class described, the combination with base and top members, of means connecting the members for raising and lowering the top member, said means including a shaft journaled on one member and having a wheel, and a brace connected to the other member and having a crank connection with the wheel.
65. 17. In an article of the class described, the combination with base and top members, of means connecting the members for raising and lowering the top member, said means including a shaft journaled on one member, arms rigidly secured to the shaft, swinging connections between the said arms and the other member, a crank element carried by the shaft, and a brace pivoted to said other member and connected to the crank element.
70. 18. In an article of the class described, the combination with a base member, of a top member, shafts journaled on the top member, standards, each comprising sections hinged together, certain of said sections being pivoted to the base member, the others being rigidly affixed to the shafts, connections between the shafts including crank elements, and crossed braces pivoted to the base member 75 and having connections with the crank elements.
75. 19. In an article of the class described, the combination with base and top members, of means for elevating and lowering the top member including folding standards connecting the members and comprising swinging hingedly connected sections, and means for moving the standards including an actuating device that interlocks with one of the 80 swinging sections of said standards for holding the said moving means and top member 85 against movement.
80. 20. In an article of the class described, the combination with base and top members, of means movable with respect to both members for elevating and lowering the top member, said means including an actuating crank arm, and a handle slidably mounted on the arm and constituting with said arm 85 a lock that engages the said movable elevating and lowering means for holding said means against movement.
85. 21. In an article of the class described, the combination with base and top members, of means for elevating the top member, said means including a shaft journaled on one member, standards comprising hingedly connected sections, certain of the sections being connected to the shaft, the other sections 90 being pivoted to the other member, means for rotating the shaft, and a brace having a crank connection with the shaft and a pivotal connection with the said other member.
90. 22. In an article of the class described, the combination with base and top members, of means for elevating the top member, said means including a shaft journaled on one end of one member, standards comprising hingedly connected sections, certain of the 95

sections being connected to the shaft, the other sections being pivoted to the corresponding end of the other member, means for rotating the shaft, and a brace having a crank connection with the shaft between the standards and a pivotal connection with the other end of said other member.

23. In an article of the class described, the combination with relatively movable base and top members, of casters carried by the base member and movable thereon into projecting relation with respect to said member, and means operated by the other member for effecting the projection of said casters.

24. In an article of the class described, the combination with a base member, of a top member movable to a position upon the same, casters carried by the base member and movable thereon into projecting relation with respect to said member, and means associated with the casters, operated by the top member, and movable upon the base member for effecting the projection of said casters.

25. In an article of the class described, the combination with a base member, of a top member movable to a position upon the same, casters carried by the base member and movable to positions below the bottom of said member, and plungers movable on the base member and carrying the casters, said top member being arranged to operate upon the plungers and thereby effect the projection of the casters.

26. In an article of the class described, the combination with a base member having legs, of plungers slidably mounted in the legs and projecting above the base member, casters carried by the lower ends of the plungers and movable to positions above the lower ends of the legs, and a top member movable to a position upon the base member, said top member being arranged to engage the upper ends of the plungers and effecting the relative movement of the base member and plungers to project the casters.

27. In an article of the class described, the combination with relatively movable members, of casters carried by one member and movable thereon into projecting relation 50 with respect to said member, means operated by the other member upon the relative movement of said members toward each other for effecting the projection of said casters, and means connecting the members for relatively moving the members towards each other and thereby effecting the projection of the casters.

28. In an article of the class described, the combination with a base member, of a top member movable to a position upon the base member, casters carried by the base member and movable thereon into projecting relation with respect to said member, means associated with the casters and operated by the top 60 member when placed upon the base member for effecting the projection of such casters, and means for elevating the top member above and lowering it upon the base member, said means also effecting the relative movement of the members to effect the projection of the casters.

29. In an article of the class described, the combination with a base member having legs, of upright plungers slidably mounted in the 75 legs and projecting above the base member, casters carried by the lower ends of the plungers, a top member arranged to rest upon the base member and engage the upper ends of the plungers, and means connecting the 80 members for elevating the top member, said means also effecting the movement of said members towards each other to effect the projection of the casters.

In testimony, that I claim the foregoing as 85 my own, I have hereto affixed my signature in the presence of two witnesses.

NATHANIEL B. STONE.

Witnesses:
